UNITED STATES PATENT OFFICE.

ALFRED L. SCRANTON, OF ROCHELLE, ILLINOIS, ASSIGNOR OF ONE-HALF
TO ABNER R. SCRANTON, OF SAME PLACE.

DOOR-LATCH.

SPECIFICATION forming part of Letters Patent No. 284,336, dated September 4, 1883.

Application filed March 27, 1883. (No model.)

To all whom it may concern:

Be it known that I, ALFRED L. SCRANTON, of Rochelle, in the county of Ogle and State of Illinois, have invented certain new and useful

5 Improvements in Combined Door-Handles, &c.; and I do hereby declare the following to be a full, clear, and exact description of the invention, such as will enable others skilled in the art to which it appertains to make and use 10 the same.

My invention relates to a combined door handle, latch, and hasp, the object being to provide a neat, cheap, and durable device of this character adapted for use with either a 15 sliding or hinged door, and reversible to admit of its attachment to either a right or left hand door.

The invention consists in the improved construction and combinations of parts herein- 20 after fully described, and pointed out in the claims.

In the drawings, Figure 1 illustrates a combined sliding and hinged door provided with my improvement. Fig. 2 is a perspective view 25 of the combined handle, latch, and hasp detached.

A represents the catch-plate of the latch adapted to be secured to the frame of the door and provided with a catch, *a*, and a perforated 30 lug, *a'*.

B represents the base-plate of the latch and handle, having secured thereto a latch-plate, C, adapted to be secured to the edge of a door to register with the catch-plate A. This plate 35 C is provided with a projecting lug, *c*, and with a vertical slot, *c'*, through which latter the latch D projects. Said latch is pivotally secured to the base-plate B by a pin, *d*, and is formed with an extension, E, bent upon the 40 latch to form a handle, F; but, if preferred, the handle may be formed of a separate piece of material and be secured to the latch. The end of the latch is formed with the usual slots or recesses *f f* to adapt it to engage the latch-

plate A. When the door is closed it will be 45 observed that the lugs *a'* and *c* will register with each other to form a hasp to receive a padlock or other fastening.

The combined latch and handle is very simple in construction, and is adapted for use 50 upon doors or gates of all kinds, whether hinged or sliding.

It will be apparent that many slight alterations in the details of my improvement may be made without departing from the spirit of 55 my invention; hence I would have it understood that I do not limit myself to the exact construction here shown and described, but reserve to myself the right to make all such changes and alterations in the details of construction as may properly fall within the scope 60 of my invention.

Having fully described my invention, what I claim as new, and desire to secure by Letters Patent, is—

1. In a combined door-handle, latch, and hasp, the combination, with a catch-plate provided with a perforated lug, of a latch-plate, having a corresponding perforated lug and a base-plate, and a combined latch and handle 70 pivotally secured to said base-plate, substantially as set forth.

2. The combination, with the catch-plate provided with a catch and a hasp extension, of a base-plate and latch-plate, the latter being 75 provided with a slot to receive the latch, and a hasp-extension adapted to register with the catch-plate, and a latch pivotally secured to said base-plate and bent upon itself to form a handle, substantially as set forth.

In testimony whereof I have signed this specification in the presence of two subscribing witnesses.

ALFRED L. SCRANTON.
